DESIGN FOR A SIGN

Harry D. Finch, Los Angeles, Calif.

Application August 4, 1938, Serial No. 79,091

Term of patent 3½ years

To all whom it may concern:

Be it known that I, Harry D. Finch, a citizen of the United States and residing at Los Angeles, in the county of Los Angeles and State of California, have invented a new, original, and ornamental Design for a Sign, of which the following is a specification, reference being had to the accompanying drawing, forming part thereof, in which:

Fig. 1 is a perspective view of the sign showing my new design.

Fig. 2 is a front elevational view.

Fig. 3 is an end view.

I claim:

The ornamental design for a sign, as shown.

HARRY D. FINCH.
